TELEPHONE RECORDER CABINET

Assen Jordanoff, New York, N. Y., assignor, by mesne assignments, to Jordaphone Corporation of America, New York, N. Y., a corporation of New York

Application February 10, 1949, Serial No. 780

Term of patent 3½ years

(Cl. D26—14)

To all whom it may concern:

Be it known that I, Assen Jordanoff, a citizen of the United States of America and a resident of the city, county, and State of New York, whose post-office address is 44 East 67th Street, New York, N. Y., have invented a new, original, and ornamental Design for a Telephone Recorder Cabinet, of which the following is a specification, reference being had to the accompanying drawing, forming a part thereof.

In the drawing, the figure is a perspective view of a telephone recorder cabinet showing my design.

The dominant features of my design reside in that portion shown in the full lines in the drawing.

I claim:

The ornamental design for a telephone recorder cabinet substantially as shown and described.

ASSEN JORDANOFF.
